(57) **CLAIM**

The ornamental design for a cup, as shown and described.

DESCRIPTION

FIG. 1 is a front side perspective view of a cup showing my new design.

FIG. 2 is a front view of a cup.

FIG. 3 is a rear view of a cup.

FIG. 4 is a left side view of a cup.

FIG. 5 is a right side view of a cup.

FIG. 6 is a top view of a cup.

FIG. 7 is a bottom view of a cup.

FIG. 8 is a rear, left side perspective view of a cup; and, FIG. 9 is an enlarged detail view of area 9 shown in FIG. 3. The broken lines in the drawings depict portions of the cup that form no part of the claimed design.
